UNITED STATES PATENT OFFICE.

BERNAT M. KLEIN AND SAMUEL WALD, OF NEW YORK, N. Y.

SHOESTRING FASTENER.

Application filed May 27, 1922. Serial No. 564,046.

To all whom it may concern:

Be it known that we, BERNAT M. KLEIN and SAMUEL WALD, both citizens of the United States, and residents of the city of 5 New York, borough of Manhattan, in the county and State of New York, have invented a new and Improved Shoestring Fastener, of which the following is a full, clear, and exact description.

10 The present invention relates to a new and improved fastener for shoe strings, and it is one of the primary objects to provide a shoe-string holder which is simple in construction and operation.

15 It is another object of the invention to provide a shoe-string holder which is readily attached to the upper edge of a shoe to receive the loops of the knot of the shoe lace.

It is a further object of the invention to 20 provide a shoe-lace holder which is adjustable toward and away from the lacing opening of the shoe to adapt the shoe-lace holder to loops of various lengths.

It is a still further object of the invention 25 to provide a shoe-lace holder which permits of the shoe lace being quickly and easily fastened and removed by the user.

With the above and other objects in view, 30 reference is had to the accompanying drawings, in which—

Figure 1 is a perspective view of a shoe having mounted thereon a shoe-lace holder constructed in accordance with the present invention;

35 Fig. 2 is a longitudinal sectional view taken on the line 2—2 of Fig. 1;

Fig. 3 is a transverse sectional view on the line 3—3 of Fig. 2.

Referring more particularly to the drawings, the reference character 11 designates 40 the shoe upper, 12 the lacing opening thereof, and 13 the shoe lace. The reference character 14 designates the edge of the foot opening of the shoe.

45 The reference character 15 designates the shoe-lace holder and said holder comprises a substantially U-shaped member 16 formed of resilient metal. This member 16 is adapted to receive the edge 14 of the foot opening 50 of the upper 11 of the shoe. One of the legs of the U-shaped member 16 is provided with oppositely disposed integral prongs 17 adapted to engage the upper 11 of the shoe to prevent a rocking of the U-shaped

member 16 relative thereto. These prongs 55 17 are not permanently attached to the shoe upper 11 but merely engage the same under the influence of the resiliency of the metal from which the U-shaped member is formed to prevent a rocking of the U-shaped member 60 relative to the shoe upper, and, at the same time, permit of adjustment of the U-shaped member relative to the shoe upper. The leg of the U-shaped member on which these prongs are formed has its lower end 65 rounded as at 14' to prevent the same from tearing the stockings of the wearer.

The reference character 20 designates a clasp member formed of resilient sheet metal and said resilient clasp member is secured 70 to one of the legs of the U-shaped member 16, as indicated by the reference character 21. As indicated by the reference character 22, the clasp member 20 is bowed as at 20' to occupy a position in spaced relation to 75 the U-shaped member 16, and the lower end of the clasp member 20 is curved as at 23, to provide an entrant space 24 between the resilient clasp member 23 and the shoe upper 11. 80

The device operates in the following manner:

One of the clasps is employed upon each side of the lacing opening 12 of the shoe upper and said clasp is positioned in such a manner that it will be close enough to the lacing opening 12 to receive the loops of the shoe lace 13. After the lace has been tied, the loops 25 are inserted beneath the resilient clasp member 20, where they will be 85 retained until such time as it is desired to remove the same. In removing the loops the same are grasped and moved downwardly so that they disengage from the resilient clasp member when the lace is free 90 to be untied. 95

From the foregoing it is apparent that the present invention provides a new and useful improvement in shoe-lace holders, which is not only adjustable relative to the 100 foot opening of the shoe but which permits of free and easy attachment and removal of the loops forming the knot of the shoe lace. Furthermore, the invention provides means for preventing a rocking movement 105 of the shoe-lace holder relative to the shoe.

What is claimed is:

A shoe-lace holder comprising a substan-

tially U-shaped member of resilient metal adapted to receive the edge of the foot opening of a shoe, integral prongs formed on the opposite side edges of one of the legs of said U-shaped member for engagement with the shoe upper to prevent rocking movement of the holder relative to the shoe upper, and

a resilient clasp secured to said U-shaped member and adapted to receive the loops of the knot of the lace of the shoe, said clasp being open in the same direction as the U-shaped member. 10

BERNAT M. KLEIN,
SAMUEL WALD.
